(57) **CLAIM**

The ornamental design for a binding machine, as shown and described.

DESCRIPTION

FIG. 1 is a front, right, and top perspective view of a binding machine, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of the area labeled 9 in FIG. 1; and,

FIG. 10 is an enlarged view of the area labeled 10 in FIG. 1.

The evenly spaced broken lines shown in the drawings depict portions of the binding machine that form no part of

(Continued)

the claimed design. The short-and-long dash broken lines indicating the enlargement portions of the design form no part of the claimed design.
